ADJUSTABLE LENGTH CARTRIDGE FOR RECORD CARDS AND THE LIKE

Robert J. Laybourn and Lawrence A. Wilson, San Jose,
Calif., assignors to International Business Machines
Corporation, Armonk, N.Y., a corporation of New
York

Filed Aug. 18, 1967, Ser. No. 8,321

Term of patent 14 years

Int. Cl. D15—99; D14—02

U.S. Cl. D26—5

FIG. 1

FIG. 2

FIG. 3

FIGURE 1 is a perspective view taken from the top, one side and one end; of an adjustable length cartridge for records and the like embodying our new design;

FIGURE 2 is a top view thereof; and

FIGURE 3 is a bottom view thereof.

The end opposite that shown in FIGURE 1 of the adjustable length cartridge, not shown, is substantially plain and unornamented.

We claim:

The ornamental design for an adjustable length cartridge for record cards and the like, as shown and described.
